UNITED STATES PATENT OFFICE.

MICHAL BARAN, OF HARVEY, ILLINOIS.

FURNACE.

Application filed November 19, 1927. Serial No. 234,360.

The present invention relates to furnaces or hot air heating plants and its main object is the provision of means in a furnace for maintaining uniform temperature throughout its length.

Another object of the invention is the provision of multiple hot air circulating means for maintaining uniform temperature in the furnace.

10 A still further object of the invention is to generally improve the construction of furnaces.

With the above general objects in view and others that will appear as the nature of the invention is better understood the same consists in the novel construction, combination and arrangement of parts hereinafter more fully described, illustrated in the accompanying drawings and pointed out in the appended 20 claims.

In the drawings forming a part of this application, and in which like designating characters refer to corresponding parts throughout the several views.

25 Fig. 1 is a cross sectional view of the furnace, the view having been taken on horizontal plane on line 1—1 of Fig. 2;

Fig. 2 is a transverse sectional view of the furnace on line 2—2 of Fig. 1;

30 Fig. 3 is a longitudinal cross sectional view on line 3—3 of Fig. 2;

Fig. 4 is a fragmentary cross sectional view on line 4—4 of Fig. 1; and

35 Fig. 5 is a cross sectional view taken on line 5—5 of Fig. 2.

Referring to the drawings in detail the furnace includes front wall 10, rear wall 11, side walls 12 and floor 14. Said floor 14 does not extend to the very front end of the furnace, but forms downwardly as at 15, and then forwardly as at 16 to provide ash pit 17. On line with said floor 14 and above said ash pit 17 is grate 18. Above said grate 18 is fire box 19 which is enclosed by side walls 20 and arcuate ceiling 21, which provides a floor for heating chamber 22, as clearly seen on Fig. 2. Said arcuate ceiling 21, has lateral continuations 21' for completing the floor of heating or muffle chamber 22.

40 50 The forward end of said fire box 19 is provided with door 23 through which fuel is supplied to said fire box 19, and door 24 positioned below said door 23 provides communication with the ash pit 17 for removing ashes.

55 Communicating with said fire chamber 19

on each side thereof through wall 20 is a plurality of passages 25 which are in spaced relation. Said passages 25 are immediately above floor 14 as clearly seen on Figs. 2 and 3, and lead laterally, extending outwardly and beyond side walls 12. Then said passages 25 turn upwardly and then horizontally toward the center of the furnace, and at points beyond the inner surfaces of walls 12 said passages 25 join and communicate with housing 60 65 26.

Said housing 26 at its top is enclosed by arcuate wall 27 which forms a partition between heating chamber 22 and said housing 26. The arcuate wall 28 joined at its side 70 edges with side walls 12, constitutes the upper closure for said housing 26. Said housing 26 is further enclosed by wall 10 at its front, wall 11 at its rear and walls 12 at its sides. 75

It is observed that the ends of arcuate wall 27 are spaced from side walls 12 and connected with portions 21' of the floor of said heating chamber 22.

It is observed that the combustion gases 80 and hot air pass from the combustion chamber 19 to said housing 26 through said passages 25, there being no other communications between said combustion chamber 19 and said housing 26. 85

For forming the outer portions of said passages 25 at points where the upright portions thereof are located box-like structures 29 are provided beyond walls 12 and laterally thereof. It is further observed that the sides of 90 said passages 25 are lined with walls 30, which in their continuity merge with the side walls 30 of the box-like structures 29. Above each passage 25 partition wall 31 is provided which constitutes the ceiling for each of said 95 passages 25. By their ends said partition walls 31 extend beyond the outer faces of side walls 12, and constitute lower walls for the upright portions of said passages 25.

Each of said box-like structures 29 is provided with plugs 32 fitting in their respective bores made in said structures which provide access to passages 25 for the purpose of either removing ashes collected upon the upper face of partition wall 31 or for supervision of 100 the proper operation of dampers 33 which will be hereinafter described. Immediately below each plug 32 temperature gages are provided by means of which the temperature 105 of gages and hot air passing through pas- 110

sages 25 from combustion chamber 19 to housing 26 may be ascertained.

It is further observed that the widths of said passages 25 are not uniform, but the same increase as the distance of said passages 25 from the fire box becomes greater. In other words the passages which are nearer to the fire over the grate 18 are smaller in width than the passages farther removed therefrom. This arrangement is made for the purpose to distribute the temperature of hot air and combustion gases which pass from combustion chamber 19 to housing 26 through passages 25, uniformly lengthwise of the housing 26 that the heating chamber 22 may be uniformly heated throughout its length.

In order to insure perfect distribution of temperature in the housing 26 lengthwise thereof, the dampers 33 are provided, which are positioned upon walls 12. Said dampers 33 in cooperation with the outer ends of partition walls 31 are capable of regulating the size of each of the passages at their upper horizontal portions or closing the passages entirely when necessary. Therefore, to insure a perfect distribution of the temperature in the housing 26 for the purposes stated said dampers 33 become of great service. Thus when any one of said dampers 33 is shifted downwardly for decreasing the size of any given passage 25, less heating air and combustion gases will be supplied through the given passage 25, and the lesser amount of gas and hot air is permitted to pass through such passage 25 the temperature in the housing 26 at a given point will be decreased or vice versa.

The arcuate wall or roof 28 of housing 26 at its rear end adjacent the rear wall 11 is provided with an opening 35, and a similar opening 36 is made at the front end of said roof adjacent the front wall 10. Said opening 35 communicates with channel 37 which is positioned adjacent the upper portion of rear wall 11 and which at its central portion remains in contact with the periphery of roof 28. Said channel 37 at one of its ends connects with a similar channel 38, which latter channel is wider than channel 37. Said channel 38 is disposed adjacent the upper end of side walls 12, and by its other end connects with a still wider channel 39 which is positioned adjacent the upper end of front wall 10. Opening 36 in the roof 28 connects with said channel 39.

Said last named channel 39 at its other end connects with a still wider channel 40 which is positioned adjacent the upper end of the other side wall 12, all of said four channels being positioned upon the same horizontal plane as seen on Figs. 2 and 3.

Said last mentioned channel 40 by its other end does not connect with channel 37, but blocks the same by one of its walls as at 41.

From the hereinabove description it will

be seen that the air and combustion gases collected in housing 26 will escape through opening 35 into channel 37 and through opening 36 into channel 38, and then through channel 37, 38, 39 and 40 will pass into chimney 42. The end of channel 40 adjacent chimney 42 leads into an upright opening 43 and connects with horizontal passage 44, both made in the chimney wall 45, which opening 44 connects with chimney 42. This arrangement slows up the escape of the combustion gases into chimney 42, and thus preserves the maximum temperature in the furnace.

All of said channels 37, 38, 39 and 40 are covered with top wall 46 which provides a ceiling for the entire furnace, as seen on Fig. 2.

The rear end of heating chamber 22 is open as at 46' through which objects to be heated in said heating chamber are hauled into or out of said heating chamber. By means of door 47 said opening 46' may be closed. Said door 47 made of the same material from which the entire furnace is constructed, has an outer lining 48 and is reenforced at its edges by angle irons 49. Said door 47 is adapted for upright sliding within a pair of brackets 50 positioned adjacent the upright sides of said door 47. For preventing said door to shift downwardly a horizontal supporting bracket 51 is provided which maintains said door 47 in position when the same remains in its operative condition as shown on Fig. 3.

The furnace shown in the accompanying drawings and described hereinabove although preferably is to be made of fire-proof brick may also be built out of concrete or any other suitable material.

While there is described herein a preferred embodiment of the present invention, it is nevertheless to be understood that minor changes may be made therein without departing from the spirit and scope of the invention as claimed.

What I claim as new is:

1. A furnace of the type defined and having a combustion chamber and fire box, a muffle chamber above the combustion chamber, an arch above the muffle chamber forming a passage for hot gases, said combustion chamber communicating with the space beneath the arch and above the muffle chamber through tortuous passages in a vertical plane, partition walls forming the passages, and the walls of the furnace having openings which communicate with the horizontal sections of the tortuous passages for clean out purposes.

2. A furnace of the type defined and having a combustion chamber and fire box, a muffle chamber above the combustion chamber, an arch above the muffle chamber forming a passage for hot gases, said combustion chamber communicating with the space beneath the arch and above the muffle chamber through

tortuous passage ways in a vertical plane, partition walls forming the passage ways, the walls of the furnace having openings which communicate with the horizontal sections of the tortuous passage ways for clean out purposes, said partition walls constituting shelves or trays upon which ashes and soot collect, and certain of the clean out openings being above the partition walls to give access

10 to the same.

3. A furnace of the type defined and having a combustion chamber and fire box, a muffle chamber above the combustion chamber, an arch above the muffle chamber forming a passage for hot gases, lateral box like extensions at the sides of the furnace near its base, said combustion chamber communicating with the

space beneath the arch and above the muffle chamber through tortuous passage ways in a vertical plane, and partly located in the lateral box-like extensions at the sides of the furnace, means carried by the extensions and movable in a vertical plane for regulating the size of the passages, partition walls forming the passages, the walls of the extensions having openings which communicate with the horizontal sections of the tortuous passage ways for clean out purposes, said partition walls constituting shelves or trays upon which ashes and soot collect, and certain of the clean out openings being above the partition walls to give access to the same.

In testimony whereof I affix my signature
MICHAEL BARAN.
